A. E. RHOADES

AUTOMATICALLY THREADING SHUTTLE FOR LOOMS

Filed Nov. 7, 1925

INVENTOR:
Alonzo C. Rhodes
BY D. H. Harris,

ATTORNEY

UNITED STATES PATENT OFFICE.

ALONZO E. RHOADES, OF HOPEDALE, MASSACHUSETTS, ASSIGNOR TO DRAPER CORPORATION, OF HOPEDALE, MASSACHUSETTS, A CORPORATION OF MAINE.

AUTOMATICALLY-THREADING SHUTTLE FOR LOOMS.

Application filed November 7, 1925. Serial No. 67,525.

To all whom it may concern:

Be it known that I, ALONZO E. RHOADES, a citizen of the United States, residing in Hopedale, in the county of Worcester and State of Massachusetts, have invented an Improvement in Automatically-Threading Shuttles for Looms, of which the following description, in connection with the accompanying drawings, is a specification, like characters on the drawings representing like parts.

This invention relates to automatically threading shuttles for looms and is directed more particularly to the threading block, whereby, during the operation of the loom, the shuttle may be threaded.

In the patent to Edward S. Stimpson, No. 1,538,224, May 19, 1925, there is shown and described a threading block for automatically threading shuttles, formed of cast iron having the thread engaging surfaces thereof covered by a rust-proof covering, and shuttles provided with such threading blocks have gone into extensive use with satisfactory results. The cast iron threading block is very hard and not capable of being satisfactorily worked or bent, and in connection with such threading block the shuttle is usually provided with a threading block receiving chamber in which the threading block is secured. It is sometimes desirable to fit the threading block into the threading block receiving chamber of the shuttle, without, however, materially altering the shape of the chamber itself or cutting away the wood of the shuttle, and one of the objects of the present invention is to provide a threading block formed in part of cast iron having a rust-proof covering on the thread engaging portions, and in part of a softer metal which may be readily worked or bent, if desired, in order to fit the block accurately to the shuttle chamber and to alter the shape of certain portions of the block to adapt it for accurate loom threading and subsequent weaving.

In accordance with one aspect of the present invention, the threading block is formed of two parts, although the number of such parts may be varied, and one of such parts, the main portion of the threading block preferably, is formed of cast iron with a rust-proof covering which offers no objectionable obstruction to the movement of the thread during weaving, and associ-

ated with such cast iron main portion of the threading block is a part, preferably constituting one side of the completed block, and formed of a softer metal such as brass which may be bent or worked readily to adapt the block to the threading block receiving chamber and the parts of the block to the shuttle wood. Threading blocks of the present invention, while adapted to new shuttles, present many advantages to renewals, that is, where an old wooden shuttle has been worn out or has become unserviceable.

The invention and new combination of parts will best be made clear from the following description and the accompanying drawings of one good practical form thereof wherein the threading block is formed of two parts, one of which is cast iron and the other of which is of a softer metal. 75

In the drawings:

Fig. 1 is a perspective view of the threading end of a shuttle provided with the present invention;

Fig. 2 is a perspective view of the main portion of the threading block which is formed of cast iron having a rust-proof covering;

Fig. 3 is a detached view of one good form of thread casting device which may be employed in connection with shuttles of this general type;

Fig. 4 is a perspective view of that part of the threading block which is formed of softer metal than cast iron and preferably brass which may be readily worked or bent to shape;

Fig. 5 is a side elevation of the threading block detached and with the cast iron and softer metal parts in their assembled relation;

Fig. 6 is a section on the line 6—6 of Fig. 5; and

Fig. 7 is a threading block constructed in accordance with the present invention but showing a modification.

The shuttle 1 may be of usual character for supporting the filling carrier or bobbin 2 and, as usual in such filling replenishing shuttles, it is provided with a bottom opening 3 for the ejection of the filling carrier on replenishment. 105

At the front end portion of the shuttle, that is the end of the shuttle containing the side delivery eye, the wood of the shuttle 110

is cut away to provide a threading block receiving chamber 4 in which the threading block constituting the present invention may be secured.

5 In its broader aspects the present invention aims to provide a threading block formed partly of cast iron having a rust-proof covering on the thread engaging portions thereof, and in part of a metal softer 10 than the cast iron which may be readily worked while cold into the desired shape, should a change in such shape be required by the shuttle to which the threading block is applied.

15 As shown in the present instance of the invention, the main portion of the threading block, as indicated in Fig. 2, is formed of cast iron having a rust-proof covering on the thread engaging portions thereof.

20 The main portion of the threading block, as indicated in Fig. 2, is formed of a bottom 5 and a side wall 6, shown as cast integral in the present instance, and providing between the two a longitudinally extending 25 thread passage 7. At the front of the thread passage 7 is the bridge 8 over which the thread passes during weaving on its way to the side delivery eye, and the cast iron part of the threading block, in the present instance, is provided with a supporting shoulder 9 which underlies a horn of the softer metal as will presently appear. The shoulder 9 is cast with the main portion of the threading block and is provided with a recess or guide 10 under which the thread passes from the longitudinally extending thread passage to the side delivery eye.

30 The other part of the threading block, as indicated in Fig. 4, consists of the side 40 member 11 which is formed of softer metal than the main portion of the threading block and preferably of brass. The side member 11 has a frontwardly extending thread director 12 which may be of usual 45 character, the end portion 13 of which extends laterally of the longitudinal thread passage. Below the thread director 12 the side portion is provided with a recess 14 shaped to fit the shoulder 9, so that the side 50 portion 11 which is formed of soft metal rests upon the cast iron shoulder 9 and finds support thereon. The construction of the main portion of the threading block, that formed of cast iron is shown in Fig. 2, and 55 the side portion 11 of the threading block which is formed of softer metal such as brass, may be variously contrived, but the construction hereinbefore described is found to be a good practical embodiment of the 60 invention.

65 The side portion 11 of softer metal is also provided with a recess 15 on its inner face which encloses a lug 16 formed on and preferably cast with the cast iron portion of the threading block, as indicated in Fig. 2, and

a pin 17 serves to properly position the parts indicated in Figs. 2 and 4 to bring them into registering relation by means of the hole 18 in the side portion 11.

Both the cast iron part of the threading block and the softer metal side portion 11 thereof are provided with openings 19 and 20, respectively, to receive the transversely extending securing bolt 21 whereby the parts of the block in their assembled relation may be secured in the threading block receiving chamber of the shuttle.

The side portion 11 above the recess 15 has a shoulder 22 which rests upon the top 23 of the lug 16 of the cast iron part of the block.

When the parts are assembled with the interengaging recesses and projections hereinbefore described, they are maintained rigidly in assembled relation when in the threading block receiving chamber of the shuttle, and while the particulars and details hereinbefore described are well-adapted for a threading block formed in part of cast iron with a rust-proof covering and in part of a softer metal that may be more readily worked, it is to be understood that applicant regards himself as being the first in the art to provide a threading block for automatically threading shuttles formed in separate parts, one of cast iron having a rust-proof covering and the other of a softer metal which may be more readily worked or bent to shape while cold, such as brass.

70 The threading block herein shown and described may be advantageously employed in connection with a thread casting device for casting the thread on the occurrence of a loop or overthrow, and in the present instance of the invention the thread casting device is shown as a scroll 24, illustrated 75 separately in Fig. 3, which has a foot portion 25 adapted to underlie the rabbeted portion 26 formed in the cast iron part of the threading block. In the present instance, the thread guiding device has an opening 27 through which the transverse bolt 21 may pass to secure the thread casting device in position in the thread passage, and in order 80 that the thread casting device may be supported in different positions longitudinally of the thread passage, the opening 27 is formed duplex. By passing the transverse bolt 21 through the parts of the threading block and through the rear opening 27 of the thread casting device, the latter will be 85 further forward in the longitudinally extending thread passage; whereas, when the front or other portion 27 of the opening in the thread casting device serves for the passage of the transverse bolt 21, the thread casting device will be nearer the bobbin chamber.

90 The softer metal side member 11 as hereinbefore described, not only has the thread 95

director 12 with its transversely extending end portion 13 but, in the present instance, has the apron 28 which extends laterally from the thread passage and overlies the 5 side delivery eye, substantially as is usual in the aprons of the prior art.

Where the threading block is formed of two parts, as indicated in Figs. 2 and 4, one of cast iron and the other of softer 10 metal, the cast iron portion provides a wall 6 at one side of the longitudinally extending thread passage, while the side member 11 of the softer metal constitutes the opposite side wall of the longitudinally extending thread 15 passage, and if desired the two walls may be substantially co-extensive.

It is sometimes desirable to provide a horn extending from the side member 11 of softer metal, as indicated in Fig. 7, and in such 20 case the side member 11 is extended somewhat further towards the bobbin chamber, as indicated in Fig. 7, and at its portion 25 adjacent the bobbin chamber it is provided with the laterally extending horn 29, the purpose of which is two-fold; first, to take control of the thread on the first pick following replenishment should the thread fail to pass into control of the thread casting device; and, second, to act as a leader for the 30 thread on the second pick following replenishment should the shuttle be only partially threaded. This latter function is performed by the concave front surface of the horn 29 over which the thread may pass 35 on its way from the bobbin to the cloth selvage on the second pick following replenishment.

The pin 17 when used to unite the cast iron and soft metal parts of the threading 40 block may extend through both portions 5 and 11, as indicated in Fig. 6, with the ends of the pin flush with the outer surfaces of the side walls, and while such pin is desirable in many cases, its use is not indispensable 45 because the cast iron portion of the block and the softer metal portion are both held in the threading block receiving chamber by the transverse bolt 21, and said two portions of the threading block have interengaging 50 supporting surfaces as hereinbefore described.

When applying the two-part threading block of the present invention to the wood of a loom shuttle, should it be found that 55 some change or alteration is desirable in the threading block to cause it to properly fit the threading block receiving chamber in the shuttle, the softer member 11 of the threading block permits ready working of 60 said part as by filing or grinding or bending, so that the threading block may be readily adapted to the conditions of the shuttle.

What is claimed is:

1. As an article of manufacture, a thread- 65 ing block for automatically threading loom

shuttles formed in part of cast iron having the thread engaging portions thereof overlaid by a rust-proof covering and a complementary part formed of a softer metal capable of being worked to fit the block to the 70 shuttle wood.

2. As an article of manufacture, a thread- 75 ing block for loom shuttles having a longitudinally extending thread passage, one side portion of the block being formed of cast iron and the other side portion being formed of a softer metal capable of being worked to fit the block to the shuttle wood.

3. As an article of manufacture, a thread- 80 ing block for loom shuttles having a longitudinally extending thread passage, one side portion of the block being formed of cast iron and the other side portion being formed of a softer metal capable of being worked to fit the block to the shuttle wood, and 85 means for securing the parts of the threading block together.

4. An automatically threading loom shuttle having a threading block receiving chamber, a threading block formed in part of cast 90 iron having the thread engaging portion overlaid by a rust-proof covering and a complementary part formed of a softer material capable of being worked to conform the 95 block to the shuttle.

5. A threading block for automatically 100 threading loom shuttles formed of separate parts, one of which is cast iron having a rust-proof covering on the thread engaging portion thereof and another part formed of a softer metal capable of being worked to the desired form.

6. A threading block for automatically 105 threading loom shuttles formed of separate parts, one of which is cast iron having a rust-proof covering on the thread engaging portions thereof and another part formed of brass capable of being worked and shaped to the desired form.

7. An automatically threading loom shuttle having a threading block formed in two parts, one of which is cast iron having a rust-proof covering on the thread engaging portions thereof, and the other of which is formed of a softer metal having a thread 115 director extending transversely relative to the longitudinal axis of the shuttle and capable of being worked to the desired form, and means for securing the parts of the threading block in assembled relation in the shuttle.

8. A threading block for automatically 120 threading loom shuttles having a part provided with a side wall formed of cast iron, the thread engaging portions of said part being overlaid by a rust-proof covering, and another side part formed of a softer metal capable of being worked or bent cold to the desired form.

9. A threading block for automatically 125

threading loom shuttles comprising two separate parts, one of which is provided with a bottom and side wall formed of cast iron, the thread engaging portions of which are protected by a rust-proof covering, and the other part of which is formed of a softer metal capable of being worked cold to the desired shape.

10. An automatically threading loom shuttle having a threading block formed in separate parts, one of which parts is cast iron having a rust-proof covering on the thread engaging portions, and another of which parts is of softer metal forming a

15 side wall of the threading block and pro-

vided with a horn extending transversely of the thread passage.

11. An automatically threading loom shuttle having a threading block formed in separate parts, one of which parts is cast-iron 20 having a rust-proof covering on the thread engaging portions, and another of which parts is of softer metal forming a side wall of the threading block and provided at its formed end with a laterally extending thread 25 director and rearward thereof with a laterally extended horn.

In testimony whereof, I have signed my name to this specification.

ALONZO E. RHOADES.
